UNITED STATES PATENT OFFICE

117,799

DESIGN FOR A DIE STOCK

Robert B. Pealer, Parkman, Ohio, assignor to Beaver Pipe Tools, Inc., Warren, Ohio, a corporation of Ohio

Application September 11, 1939, Serial No. 87,138

Term of patent 14 years

To whom it may concern:

Be it known that I, Robert B. Pealer, a citizen of the United States of America, residing at Parkman, in the county of Geauga and State of Ohio, have invented a new, original, and ornamental Design for a Die Stock, of which the following is a specification, reference being had to the accompanying drawings, forming part thereof.

In the drawings, Fig. 1 is a top plan of the die
stock embodying my new design; Fig. 2 is a side elevation thereof; Fig. 3 is a perspective view;
and Fig. 4 is a bottom plan.

I claim:

The ornamental design for a die stock, substantially as shown.

ROBERT B. PEALER.
